UNITED STATES PATENT OFFICE

152,154

DESIGN FOR A TOY AUTOMOBILE

William Edward Hoffmann, St. Louis, Mo., assignor to Timely Toys, Inc., St. Louis, Mo., a corporation of Missouri

Application October 28, 1946, Serial No. 134,350

Term of patent 14 years

(Cl. D34—15)

To all whom it may concern:

Be it known that the undersigned, William Edward Hoffmann, a citizen of the United States, residing at St. Louis, Missouri, has invented a new, original, and ornamental Design for a Toy Automobile, of which the following is a specification, reference being had to the accompanying drawing, forming a part thereof, in which:

Fig. 1 is a plan view of a toy automobile, embodying my new design;

Fig. 2 is a side elevation;

Fig. 3 is a rear view; and

Fig. 4 is a front view.

I claim:

The ornamental design for a toy automobile, substantially as shown.

WILLIAM EDWARD HOFFMANN.
